DESIGN.

C. E. HAVILAND.
HANDLE FOR DISHES.

No. 17,063.

Patented Jan. 11, 1887.

UNITED STATES PATENT OFFICE.

CHARLES EDWARD HAVILAND, OF LIMOGES, FRANCE.

DESIGN FOR A HANDLE FOR DISHES.

SPECIFICATION forming part of **Design No. 17,063**, dated **January 11, 1887**.

Application filed December 13, 1886. Serial No. 211,487. Term of patent 14 years.

To all whom it may concern:

Be it known that I, CHARLES EDWARD HAVILAND, a citizen of the United States, residing at Limoges, in the Republic of France, have invented and produced a new and original Design for Handles of Dishes, which is described and represented in the following specification and accompanying fac-similes, forming a part of the same,

Figure 1 is a perspective view of a covered dish, and Fig. 2 a like view of a cup, each provided with handles embodying this design.

The characteristic features of this handle are a bridge-like form consisting of three scroll-like formations, the middle one of which is represented as doubled upon itself. The middle scroll, A, properly curved when longitudinally considered, has one end represented

as doubled, while at the opposite end its plies are represented as turned outward in opposite directions. At each end this middle scroll is supported by simple scrolls, B C, represented with ends curled toward each other.

What is claimed is—

The design for handles of dishes, the same consisting of a bridge-like form comprising three scrolls, the middle one of which is represented as doubled upon itself at one end, substantially as shown and described.

In testimony whereof I have hereunto set my hand in the presence of two subscribing witnesses.

CH. ED. HAVILAND.

F. CATE,
A. SEXÉQUE.
